UNITED STATES PATENT OFFICE.

FRED SWAN, OF WICHITA, KANSAS.

UNDERREAMER BIT OR CUTTER.

Application filed August 5, 1925. Serial No. 48,291.

My invention relates to underreamers for enlarging a hole drilled below casing in a drilled well and particularly relates to underreamers of the solid wedge type such as 5 the Swan underreamer shown in the patent to John C. Swan, No. 683,352, dated September 24, 1901 and other patents to John Swan, in which the cutters or reaming bits slide on a wedge at the lower end of the 10 reamer body being drawn down on the wedge into collapsed position and then held as the underreamer is lowered through the casing, released as the underreamer passes below the lower end of the casing and drawn 15 up in the wedge into expanded position by a spring.

In pulling out the underreamer as the cutters or reaming bits are brought into contact with the lower end of the casing 20 their upward movement is momentarily stopped while the upward movement of the reamer body continues with the result that the wedge is drawn up from between the cutters permitting the cutters to move inward into approximately their collapsed position so that their outer faces will be within 25 a circle of the diameter of the interior of the contact of the upper portion of the outer face of the cutters with the interior 30 of the casing the cutting edges of the cutters will be held out of contact with the casing.

With casing made up of sections connected by screw joints the interior of the casing 35 is so uneven that the frictional contact of the outer faces of the cutters is amply sufficient to keep the cutters at the lower end of the wedge and prevent the cutting edges from contact with the casing and it has 40 been customary to tallow the ways in order that the cutters will move freely downward and inward if the upward movement of the cutters is checked by unusual roughness of the interior of the casing.

45 Seamless casing is now extensively used and the interior of such casing is of such smoothness that the friction between the outer faces of the cutters, as ordinarily constructed is not sufficient to hold the cutters 50 down on the wedge as the underreamer is drawn upward, to permit the underreamer to pull freely.

The invention of my present application is designed to overcome this difficulty and 55 to provide a construction of cutters which will have such frictional contact with the

smooth interior of seamless casing that the cutters will be kept so near the lower end of the wedge, and consequently so near together, that the underreamer will pull freely. 60

With the object above explained in view my invention consists in the construction hereinafter described and claimed.

Referring to the drawings Figure 1 is a vertical central section of a drilled well 65 showing an underreamer below the casing with its cutters in expanded position.

Figure 2 is a similar view but showing the underreamer drawn up into the casing.

Figure 3 is a face view of a cutter embodying my invention and 70

Figure 4 is a side view of the same.

In the drawings 1 indicates seamless casing having interior diameter D^1 indicated in Figure 2 in a drilled well hole having an 75 interior diameter D^2 . 2 indicates an underreamer body of the Swan type having at its lower end a wedge 3 on which cutters 4 are movable into and out of expanded position.

5 indicates abutments against which the 80 upper ends of the cutters are drawn by spring 6 through spring rod 7 and cross bar 8. Trips 9, as shown in the John C. Swan patent above referred to, provided on their inner ends with extensions 16, are 85 movable in slots formed in the reamer body toward and from the spring rod 7. When the cutters are drawn down to the lower ends of the ways so as to permit the underreamer to enter the upper end of the casing 90 the enlargement 10 on the spring rod is brought below the line of the extensions 16.

When the trips are pressed inward these extensions 16 engage the upper faces of the enlargement 10 and hold the spring rod 95 down against the force of spring 6 so that the spring cannot act to draw the cutters upward on their ways into expanded position. The outer faces of the cutters are thus held out of contact with the casing. The 100 trips are held during the downward movement of the underreamer through the casing by the contact of their outer ends with the casing, in position to hold the extensions in contact with the upper faces of the enlargement 10.

105 The cutter 4 is provided with grooves 11 to engage ways 12 on the wedge 3. At its lower end the cutter is provided with a cutting edge 13 formed on the arc of a 110 circle of a diameter corresponding to D^2 , the diameter to which the hole below casing

is to be enlarged. Above this cutting edge 13, the outer face 14 of the cutter 4 is inclined inward at an angle to the ways 11 and is formed on the arc of a circle having the diameter D^1 that is a diameter corresponding to the diameter of the interior of the casing and this outer face is roughened or corrugated by horizontal grooves 15.

This outer face 14 is at such angle to the grooves 11 that when the underreamer is drawn into the casing its corrugated surface will throughout its extent be in contact with the interior surface of the casing 1 that the resistance thus afforded will be as great as possible notwithstanding the smoothness of the inner surface of the pipe and will keep the cutters down on the wedge and will keep the cutting edge 13 as far

inward and away from the casing as possible.

Having thus described my invention what I claim is:—

In an underreamer of the type in which cutters are movable on tapering ways into and out of expanded position and are moved into expanded position by a spring, a cutter having a cutting edge at its lower end and having its outer face above the cutting edge inclined inward and formed on an arc of a circle corresponding in diameter to the interior diameter of the casing and roughened to increase its frictional contact with the interior of the casing.

In testimony whereof, I hereunto affix my signature.

FRED SWAN.
